UNITED STATES PATENT OFFICE.

EDWARD CLIFF, OF NEWARK, NEW JERSEY, ASSIGNOR TO THE CLIFF & GUIBERT COMPANY, OF NEW YORK, N. Y.

DESIGN FOR A BRACKET FOR HOSE-REELS.

SPECIFICATION forming part of Design No. 32,337, dated March 13, 1900.

Application filed February 12, 1900. Serial No. 5,014. Term of patent 14 years.

To all whom it may concern:

Be it known that I, EDWARD CLIFF, a citizen of the United States, residing at Newark, in the county of Essex and State of New Jersey, have invented and produced a new and original Design for a Bracket for Hose-Reels, of which the following is a specification, reference being had to the accompanying drawings, forming a part thereof, and in which—

10 Figure 1 is a top view of a bracket bearing and incorporating my design. Fig. 2 is a side elevation of same, and Fig. 3 is a vertical section through one side of same on the dotted line 3 3 of Fig. 2.

15 The leading feature of my design consists in the form and configuration of the bracket, substantially as shown in the drawings.

In the drawings, A designates the bracket as a whole, the said bracket being in the form 20 of a yoke, comprising the side arms B B and the base or transverse section C. The arms B B taper from the section C outward, so that

at their outer rounded ends said arms B B are of less height than at their portions which merge into the base-section C. At the facing 25 sides of the outer ends of the arms B B are circular hubs D, and at the center of the transverse or base section C is the vertically-disposed hub-section E. The arms B B and transverse or base section C have exterior 30 surfaces which are harmonious throughout, said surfaces at the exterior side of the bracket being convex and presenting the appearance of being in strong relief, as indicated in Fig. 3.

35

What I claim is—

The design for a bracket for hose-reels, substantially as shown and described.

Signed at New York, in the county and State of New York, this 10th day of February, 1900. 40
EDWARD CLIFF.
